H. J. Bernhard

UNITED STATES PATENT OFFICE.

ARCHIBALD F. WRIGHT, OF EAST ORANGE, NEW JERSEY, ASSIGNOR TO INDUSTRIAL DRYER CORPORATION, OF NEWARK, NEW JERSEY, A CORPORATION OF NEW JERSEY.

METHOD OF AND APPARATUS FOR DRYING.

Application filed May 20, 1920. Serial No. 382,838.

To all whom it may concern:

Be it known that I, ARCHIBALD F. WRIGHT, a citizen of the United States, residing at East Orange, county of Essex, 5 and State of New Jersey, have invented a certain new and useful Method of and Apparatus for Drying, of which the following is a specification.

This invention is a method of and apparatus for drying wherein the evaporation of moisture is conducted under such conditions as to reduce the volume of the drying agent, usually atmospheric air, in proportion to the moisture content of the material under treatment while at the same time the speed or velocity, and preferably the temperature, of such drying agent are maintained constant, as a result of which treatment there is obtained marked economy in the heat, usually 20 steam, required for the maintenance of the drying agent at the temperature necessary for the evaporation of moisture.

In the drying art, the evaporation of moisture by the flow of heated air into contact with the moist material results in carrying off a substantial percentage of the moisture during a period, say one hour, which may be considered the first stage of the treatment, and thereafter the evaporation 30 takes place more slowly during the second period, say the second hour, and as the moisture content of the mass decreases, the evaporation takes place still more slowly during the successive periods and the final 35 period of the treatment. It is usual to circulate air in a given volume per minute, and at a desired velocity and under a certain temperature, during the initial, successive and final periods in the treatment 40 of the material; but as the moisture content of the material decreases in a certain ratio during the successive and final stages of the treatment, the operation of heating the large volume of air to a predetermined temperature throughout all the stages of the treatment results in a very considerable waste 45 and loss of heat energy.

It is the purpose of this invention to conserve the energy required for the maintenance of the drying agent at the desired temperature, and at the same time to conduct the treatment with efficiency and with a material saving in the time necessary for

the evaporation of moisture from the material.

According to this invention, the volume of air utilized as the drying medium is reduced progressively and in proportion to a decrease in the moisture content of the mass, while at the same time the velocity of the 60 air, and preferably the temperature thereof, is maintained constant.

In a practical form of apparatus, means are provided for supporting the moist material in separated masses so as to establish 65 flow channels for the circulation of the drying medium, the latter being supplied in the required volume and at the desired velocity by the operation either of a blower or an exhauster, and said drying medium being 70 initially raised to a desired temperature by conducting the air into contact with an initial heater.

Means are provided for conducting the flow of the drying medium into contact with 75 the masses of moist material the area of which contact is increased in proportion to a reduction in the moisture content of the masses. Said controlling means in the embodiment of the invention comprises 80 dampers positioned in series at the respective ends of the material-supporting means, and said dampers are operable individually and in a manner to vary the operative length of the channels through which the 85 drying medium must flow.

At the initial stage, the air circulating means supplies the air in large volumes, and at proper velocity and at the required temperature, for carrying off a certain percentage of moisture, but as the moisture content decreases in the masses of material, the volume of air is proportionately decreased although the velocity and temperature of such decreased volume of air remain constant, 90 and simultaneously therewith the operative length of the air channels are increased, such decrease in the volume of air and the increase in the operative length of the air channels being effected at successive stages 95 100 in the treatment of the material, and such changes in the air volume and the length of the flow channels being proportionate to the decrease in the moisture content of the masses. The variation in the length of the 105 air channels is due to the manipulation of

the dampers, which manipulation may be effected manually, whereas the variation in the air volume is brought about either by controlling the area of the air inlet to the blower or by varying the speed of said blower, as will be readily understood by those skilled in the art.

Other functions and advantages of the invention will appear from the following description taken in connection with the drawings, wherein—

Figure 1 is a vertical longitudinal sectional view through my apparatus illustrating the dampers positioned for directing the flow of air during an early stage in the evaporation of moisture from the masses of material.

Figure 2 is a similar view of the apparatus with the dampers adjusted to a different position for controlling the flow of air during an intermediate stage of the treatment and

Figure 3 is a similar view of the apparatus with the dampers adjusted for controlling the air flow during the final stage of the evaporation.

Within a casing or housing A are provided a series of baffles B, the end portions of which terminate adjacent the end walls 30 of the housing, leaving spaces or flues C D for the circulation of the drying medium usually atmospheric air. The baffles are shown as extending horizontally within the housing, and they are spaced in parallel, or 35 substantially parallel relation to produce flow channels 1, 2, 3, 4, 5, 6, 7, 8,—eight in number, although the number may be increased or decreased as desired according to the capacity of the machine. Said flow 40 channels accommodate suitable means for supporting moist material in separated masses within the housing, the material supporting means being in the form of trays, or endless belts or conveyors, or portable 45 trucks, may be used when and where desired.

At or near one end of the housing is a chamber E for the initial heater F, the latter being shown as steam coils, although 50 other air heating means may be substituted for said steam coils. Said chamber E communicates by a port e with the first flow channel of the series, said port e being shown as positioned at the bottom of the 55 housing so that the direction of air flow will be from the bottom toward the top of said housing, although the direction of air flow may be reversed, should occasion require.

Air is circulated through the flow channel by a blower or exhauster, a blower G being shown in Figure 1 for this purpose. As is usual, the blower is provided with an axial inlet for the air, and it is connected by a wind trunk g with chamber E,

said blower operating to feed air in the required volume and at the desired velocity to said chamber E through which the air flows so as to have contact with the heater F for initially heating the air to the desired 70 temperature.

The housing A is provided with one or a plurality of outlets a for the outflow of air, laden more or less with moisture evaporated from the material under treatment, said outlet being shown as provided with a damper a'.

The flow of air within the channels is controlled by two series of dampers H I, one series being positioned within the vertical space C and the dampers of the other series lying within the other space D. Each damper is shown as a flat plate, the same being hinged in the horizontal plane of one of the baffles B. The dampers of the two 85 series are adapted for individual operation, and said dampers are movable for closing the spaces C D in a manner to control the operative length of the flow channels.

In operation, the material in separated 90 masses is introduced into the flow channels, steam is supplied to the initial heater F, and blower G is started for circulating air through the chamber E and within the flow channels. During the initial stage of the 95 evaporation, the material as a rule gives off moisture freely and a relatively large percentage of the moisture is evaporated from the material and carried off by the air flowing within the channels, for which purpose the blower is operated to feed air in maximum quantity and at a desired velocity, the air being heated by the coils F to the required temperature. At this stage in the 100 procedure, the middle damper H in the series is closed across the space C and positioned in register with the middle baffle B, all the other dampers in the series H and I being opened, as shown in Figure 1, as a 105 result of which damper adjustment the inflowing heated air circulates once through the channels 1, 2, 3, 4, thence into space D, and thence in an opposite direction within the channels 5, 6, 7, 8, as indicated by the arrows in said Figure 1, the air finding an exit 110 at a from the housing.

Air in the required volume flows through flues 1, 2, 3, 4, and thence through flues 5, 6, 7, 8, so as to contact twice with the material between the point of inlet and outlet of the housing, the air exchanging heat for moisture and operating to carry off a large percentage of moisture from the material during the first stage of the treatment, which stage may extend over a period of one hour 115 or more.

A substantial percentage of the moisture having been evaporated and carried off during the first stage and the moisture content of the material having decreased to an ap- 120

preciable extent, the dampers H I are adjusted as in Figure 2 and the blower operated to feed air in a reduced volume, although the velocity and temperature of the air remain constant. As shown in said Figure 2, the second and fifth dampers in series H and the second damper in series I are closed so as to register with the second, fourth and sixth baffles B, the effect of which 10 is to direct the inflowing air through channels 1, 2, back through channels 3, 4, thence through channels 5, 6, and back again through channels 7, 8, thence to the exit a. The dampers when adjusted as in Figure 2 15 control the flow of air in a manner to prolong the contact of the air with the moist material, the effect of the damper adjustment being to materially increase the operative length of the flow channels as compared 20 with the length of said channels shown in Figure 1. As the moisture content of the material during the second stage is decreased to an appreciable extent as compared with the moisture content of said material during 25 the first stage, the flow of air in reduced volume, although at the initial velocity and at the same temperature, during the second stage is quite sufficient for the purpose of evaporating moisture. 30 The treatment during the second stage is continued for such a period as is or may be required, say for another hour or even longer, during which period the moisture remaining in the material is further reduced 35 until the material attains a condition which requires further treatment in order to evaporate from it that relatively small percentage of moisture, which evaporation has heretofore required prolonged application 40 of heated air with the purpose in view of ultimately attaining the condition known in the art as "bone dry." It is this final stage in the treatment of the material which hitherto has been most difficult of attainment 45 and which has seriously involved the great loss and waste of the heat energy necessary to raise the large volume of air hitherto used to a temperature suitable for carrying further the evaporating process; but the loss 50 of heat incidental to prior evaporating procedures and apparatuses does not apply in my present invention, for the reason that my apparatus and procedure are controlled to attain a prolonged application of the 55 heated air in reduced volume to material containing a relatively small moisture content, the volume of the air supplied at this stage of treatment being decreased proportionately to the reduction in the moisture 60 content of the material, although the velocity and temperature of the air remain constant throughout the final period of treatment.

To attain the prolonged application of the air in reduced volume to material contain-

ing a low percentage of moisture, the dampers H I are adjusted as in Figure 3, and concurrently with such damper adjustment the blower is controlled to feed air in a smaller volume, although the air velocity 70 and the air temperature remain constant. As shown in Figure 3, the first, third, fifth and seventh dampers in series H and the three dampers in series I are closed for registration with the baffles B, in order to substantially increase the operative length of the flow channel within the housing; and thus the air flows back and forth successively through the channels 1, 2, 3, 4, 5, 6, 7 and 8, whereby the air in reduced volume has prolonged contact with the masses of material, the period of air flow under these conditions being prolonged as desirable or found necessary for the evaporation of that small percentage of moisture which is present in the material after the latter shall have been subjected to treatment during the first and subsequent stages with the apparatus adjusted as in Figures 1 and 2 respectively. 80

Having thus fully described the invention 85 what I claim as new and desire to secure by Letters Patent is:

1. In the art of drying, the process which consists in circulating a gaseous drying medium in a desired volume and at suitable 90 velocity and at a desired temperature into contact with moist material for a period of time to evaporate a certain percentage of moisture from such material; and subsequently to such period of treatment, circulating a gaseous drying medium in decreased volume, and at the same velocity and temperature, into contact with the same material, the volume of the gaseous drying medium being decreased proportionately to a 95 reduction in the moisture content of the material during the subsequent period of treatment.
2. In the art of drying, the process which consists in circulating air in relatively large 100 volume and at a desired velocity and temperature into contact with moist material for a desired period of time for effecting the evaporation of a relatively large percentage of the moisture content of such material; and subsequently to such period of treatment, 105 circulating air in decreased volume but at substantially the same velocity and temperature into contact with the same material for a further period of time to attain a desired evaporation of the remainder of the moisture from the material, the decrease in the volume of air being proportionate to a reduction in the moisture content of the material.
3. In the art of drying, the process which consists in circulating air in a desired volume and at a desired velocity and temperature through flow channels of predetermined length and into contact with moist 115

material for a given period of time to attain the evaporation of a certain percentage of moisture; progressively increasing the operative length of the flow channels during a subsequent stage or stages in the treatment of the material and concurrently therewith decreasing the volume of air, while maintaining the velocity and temperature constant, circulated into contact with such material during the successive stage or stages in the treatment thereof.

4. In the art of drying, the process which consists in circulating air into contact with moist material, and progressively decreasing the volume of air so circulated proportionately to a reduction in the moisture content of said material.

5. In a drying apparatus, encasing means provided with a succession of flow channels, the latter being unobstructed, means for circulating within said flow channels a drying atmosphere at constant velocity and temperature and in decreasing volume proportionately to an increase in the operative length

of said flow channels, means for effecting a variation in the operative length of said flow channels, and an initial heater constituting the sole means for heating the drying atmosphere.

6. In a drying apparatus, encasing means provided with a succession of flow channels, the latter being unobstructed, means for circulating within said flow channels a drying atmosphere at constant velocity and temperature and in decreasing volume proportionately to an increase in the operative length of said flow channels, means for effecting a variation in the operative length of said flow channels, and an initial heater divided to produce a tortuous channel for the flow of the drying atmosphere, said initial heater constituting the sole means for heating the drying atmosphere to a desired temperature and acting to preheat said atmosphere before admission to the flow channel.

In testimony whereof I have signed my name hereto this 19th day of May, 1920.

ARCHIBALD F. WRIGHT.
